[57] **CLAIM**

The ornamental design for a video tape recorder controller, as shown and described.

DESCRIPTION

FIG. 1 is a front, top and right side perspective view of a video tape recorder controller showing our new design, as a first embodiment;

FIG. 2 is a rear, bottom and left side perspective view thereof; and

FIG. 3 is a front, top and right side perspective view of the video tape recorder controller showing our new design as a second embodiment, the rear, bottom and left side conforming identically to that of the embodiment of FIG. 1.

FIG. 1

FIG. 2

FIG. 3
